UNITED STATES PATENT OFFICE

FAY D. KINNEY, OF SOUTHERBRIDGE, MASSACHUSETTS, ASSIGNOR TO UNITED SHOE MACHINERY CORPORATION, OF PATERSON, NEW JERSEY, A CORPORATION OF NEW JERSEY

FOXING CEMENTING MACHINE

Application filed October 16, 1929. Serial No. 400,131.

This invention relates to coating machines for shoes and is herein illustrated as embodied in a machine for applying cement to the foxing areas of tennis shoes.

Rubber soled shoes of the tennis type are provided with a foxing strip interposed between the edge of the sole and the canvas upper in order more firmly to secure the sole edge to the shoe. In accordance with the usual commercial practice and in order to provide an attractive shoe, this foxing strip is applied to the lower margins of the sides of a shoe around its periphery with its upper edge a substantially uniform distance above the bottom of the shoe, it being secured to the shoe by means of cement. Satisfactory results can only be obtained if the cement which is applied to the shoe before the foxing strip is applied lies along the foxing area in a stripe the upper edge of which exactly coincides with the upper edge of the foxing strip so as firmly to secure said upper edge to the shoe and so as not to extend above the upper edge to disfigure the shoe.

In view of the above, an object of the present invention is to provide an improved machine for applying a stripe of cement to the foxing area of a shoe, quickly, accurately and in a relatively thick coating.

The illustrated machine is of the type in which shoes are presented manually to a cement applying device in such a manner as to coat successive portions of the foxing area as the shoe is traversed past the applying device. To this end the illustrated machine, in accordance with features of the invention, provides an adjustable smooth work supporting table which lies in a fixed relation to the lower edge of a rotatable annular shield. This shield, illustrated as mounted for rotation about a fixed up-and-down axis, rolls along the upper of a shoe moved along the work supporting table and is constructed and arranged to protect the upper above the foxing area while permitting the application of cement to the foxing area of the shoe. As herein illustrated, the applying member comprises a rotary brush dipping in an underlying receptacle for cement and wiping

downwardly across the lower edge of the shield and the foxing area of a shoe. This brush, approximately the upper half of which is within and enclosed by the shield at any given time, as well as the annular shield are rotated by power to facilitate use of the machine. In the illustrated construction also, provision is made for cleaning both the inner and outer surfaces of the shield, the former to avoid an accumulation of cement, and the latter to prevent accidental application of cement to the upper of a shoe.

In the drawings,

Fig. 1 is a perspective view of the complete machine;

Fig. 2 is a fragmentary vertical sectional view through the applying brush and the work support and shield; and

Fig. 3 is a fragmentary plan view of these parts.

The machine provides a rotatable cylindrical shield 10, the free lower edge of which is exposed for the presentation thereto of a tennis shoe 12 mounted on its last 14 as the shoe is slid along the top surface of a work supporting table 16. This table is supported and adjustably positioned on the machine base 22 by means of slotted brackets 18 and 19 and bolts 20. The annular shield 10 is supported for rotation about a fixed axis by means of brackets 24 and 25 carried on the base and supporting at their upper ends a hollow frame 26. The upper end of the cylindrical shield is provided with an overhanging flanged supporting member 28 riding upon rolls 30 extending inwardly from said hollow frame 26. Superposed adjustable guide rolls 32 are also provided for engagement with the upper surface of the flanged member 28 and guide disks 34 mounted in said hollow frame 26 are arranged for engagement with the outer cylindrical surface of the flanged member 28 attached to the shield. It will thus be seen that the shield with its flanged supporting member 28 is guided for rotation around a fixed up-and-down axis and held against up-and-down movement. The edge of the flange on the member 28 is provided with a groove for the reception of a crossed belt 36 through

which power may be supplied to rotate said annular shield from any suitable source of power as indicated, for example, by the driving belt 38. The connections between said driving belt 38 and the crossed belt 36 include a horizontal shaft 40 connected by mitre gears to an upright shaft 42 at the upper end of which there is a small pulley 44 and around which the crossed belt 36 passes.

10 A cement receptacle 50 underlies the shield, being supported on a post 51, and has an outwardly extending portion 52 which underlies the point of contact between said shoe and a driven rotary applying brush 54. The relation of receptacle 50 to the brush 54 is such that the brush dips in the cement within the receptacle and wiping downwardly across the inner surface of the shield 10 and the foxing area 56 of the shoe applies cement to the latter progressively around the foxing area as an operator, positioning a shoe on the work supporting table 16, moves it past said brush in rolling contact with the shield 10. The brush 54 is journaled in upright arms 60 and 61 about a substantially horizontal axis within the shield and the brush is power driven by means of a belt 62 passing over a pulley 64 on the shaft 40. An auxiliary receptacle 66 serves to catch any drippings or spatters of cement.

15 In order to clean the inner and outer surfaces of the annular shield 10, the machine is provided with scrapers 70 and 72, mounted on pivoted arms 74, said arms being interconnected by a spring 76 to hold the scrapers into contact with the walls of the shield 10. By means of this arrangement, an accumulation of cement upon the inner surface of the shield is prevented and in case any cement is accidentally applied to the outer surface of the shield, this will be removed by the scraper 72 so that it will not be carried over to a portion of the upper of the shoe which it is desired should not be coated.

20 In the operation of the machine, a shoe will be manually presented to the applying brush 54 by sliding it along the upper surface of the work supporting table 16 with the upper of the shoe in rolling contact with the lower edge of the rotatable shield 10. A traversing movement of the shoe will make the applying brush 54 effective to coat successive portions of the foxing area 56 until a stripe of cement is applied around the 25 whole periphery of the shoe. Inasmuch as the relation of the work supporting table to the lower edge of the shield 10 is fixed, this stripe of cement will extent a substantially uniform distance above the bottom of the 30 shoe and a relatively thick coat may be applied easily and quickly, as there will be no tendency for the cement to creep up above the upper edge of the foxing area around the corner of the shield 10, partly because of the 35 downward movement of the operative face of

the applying brush 54. Since the outer surface of the annular shield 10 is kept clean by means of the scraper 72, there can be no possibility of transferring cement to the shoe upper from this shield. The annular shield 10 being power driven will not only facilitate the traversing movement of the shoe past the applying brush 54 but may to some extent serve as a work feeding member.

Having thus described my invention, what I claim as new and desire to secure by Letters Patent of the United States is:

1. In a foxing cementing machine, a frame, a smooth work supporting table adjustably positioned on said frame, a rotatably mounted hollow annular shield having its lower edge exposed for rolling contact with the upper of a shoe presented thereto in coincidence with the upper edge of the foxing area of the shoe, cement applying means associated with said shield and operable adjacent to said lower edge to apply cement to the foxing area of the shoe and to the inner surface of said shield whereby the line of demarcation is determined by the rolling contact of said shield with said shoe as the shoe is slid over the work supporting table and the operator aided in manually presenting a shoe to said shield at the desired level to coat successive portions of the foxing area. 95

2. In a foxing cementing machine, cement applying means, a shoe supporting member, and a hollow annular shield having an exposed edge arranged to permit the application of cement by said means to the foxing area of the upper of a shoe supported by said member while shielding the rest of the shoe upper from the application of cement, said shield being rotatable about a fixed axis whereby the shield rolls along the upper of the shoe upon presentation of the shoe to the cement applying means and movement of translation past said applying means to cause successive portions of the foxing area of the shoe to be coated. 100

3. In a foxing cementing machine, cement applying means, an adjustably mounted shoe supporting member, and a hollow annular shield having an exposed edge spaced from said supporting member and arranged to permit the application of cement by said means to the foxing area of the upper of a shoe on said member while shielding the rest of the shoe upper from the application of cement, said shield being rotatable about a fixed axis whereby the shield rolls along the upper of the shoe upon movement of the shoe past the cement applying means to cause successive portions of the foxing area of the shoe to be coated. 105

4. In a foxing cementing machine, an annular shield rotatable about a fixed up-and-down axis with its lower edge exposed for contact with the upper of a shoe to protect said shoe above its foxing area, means for 110

guiding a shoe presented to the shield, a power driven cement applying member carrying cement downwardly across the space between the lower edge of the shield and said guide thereby to coat successive portions of the foxing area of a shoe manually presented thereto, and a receptacle for supplying cement to said applying member.

5. In a foxing cementing machine, a rotatable cylindrical shield having its lower edge arranged for rolling contact with a shoe to shield the shoe above the foxing area thereof, power means for rotating said shield positively in the direction of feeding movement of a shoe presented thereto, a cement receptacle below said shield, and an applying member partly enclosed within said shield and constructed and arranged to wipe across the lower edge of the inside of the shield and the foxing area of the shoe presented thereto to coat successive portions of said foxing area.

6. In a foxing cementing machine, a rotatably mounted hollow annular shield constructed and arranged for contact with the upper edge of the foxing area of a shoe presented thereto, cement applying means within said shield designed to apply cement to the exposed foxing area immediately adjacent to the lower edge of the shield, and means for cleaning the outer surface of the shield that contacts with the shoe.

7. In a foxing cementing machine, a rotatably mounted annular shield having its lower edge exposed for application to the upper of a shoe, cement applying means within said shield, means for removing surplus cement from the interior of the shield, and means for cleaning the outer surface of the shield prior to its contact with the shoe.

40 8. In a foxing cementing machine, a cylindrical shield rotatable about an upright axis with its lower edge exposed for the presentation of a shoe thereto in such a position that the upper edge of the foxing area will coincide with the lower edge of the shield, means for cleaning the outer surface of the shield, and means within the shield arranged to coat the exposed foxing area of the shoe as the latter is moved to present different portions of the shoe to the shield and for coating device.

9. In a foxing cementing machine, a cylindrical shield rotatable about a fixed axis and having its lower edge free for contact with a shoe to shield the shoe above the foxing area thereof, a cement supplying receptacle fixed in position below said shield, and a brush rotatable about an axis at right angles to the rotation of the shield positioned within the shield to dip in the cement of said receptacle and to wipe across the lower edge of the inside of the shield and the foxing area of the shoe thereby to apply a stripe of cement, the upper edge of which will be determined by

the rolling contact of the shield with the shoe.

10. In a foxing cementing machine, a rotatable cylindrical shield having its lower edge free for contact with a shoe to shield the shoe above the foxing area thereof, a cement receptacle below said shield, and a brush rotatable about an axis at right angles to the axis of rotation of the shield and positioned within the shield to dip in the cement of said receptacle and to wipe across the lower edge of the inside of the shield and the foxing area of the shoe thereby to apply a stripe of cement, the upper edge of which will be determined by the rolling contact of the shield along the shoe, and a smooth work supporting plate positioned at the front of the point of application of the work to the shield, said plate being adjustably mounted and arranged to support a shoe by contact with the bottom thereof.

In testimony whereof I have signed my name to this specification.
